UNITED STATES PATENT OFFICE.

GEORGE R. PERRY, OF WASHINGTON, DISTRICT OF COLUMBIA.

COIN-TRAP.

1,158,552.

Specification of Letters Patent.

Patented Nov. 2, 1915.

Application filed February 25, 1913. Serial No. 750,556.

To all whom it may concern:

Be it known that I, GEORGE R. PERRY, a citizen of the United States, residing at Washington, in the District of Columbia, have invented certain new and useful Improvements in Coin-Traps; and I do hereby declare the following to be a full, clear, and exact description of the invention, such as will enable others skilled in the art to 10 which it appertains to make and use the same.

This invention relates to coin receptacles adapted to prevent the coins inserted therein from being removed without breaking a seal or unlocking or removing a fastening device to permit the receptacle to be opened or taken apart for the removal of the coins; the device being especially designed to be used in connection with savings banks, for 20 the purpose of inculcating the habit of saving dimes and nickels and encouraging persons whose means are limited as well as the general public to effect a saving of a part of their income in this way.

The objects of the invention are to provide a simple, efficient and inexpensive device of the character referred to, of light weight and small size, and which shall consist of few parts separably secured together 30 in compact form and adapted to receive and retain coins placed therein in such manner that after the receptacle is filled, or after the insertion of a coin, it cannot be emptied or a coin removed without breaking a seal and taking the device apart; the device being at the same time convertible into a non-locking receptacle so that, without the interposition of any other part, the user may convert the device from a locking 35 40 45 50 55 60 65 70 75 80 85 90 95 100 105 110 condition, or vice versa, by simply reversing or changing the position of certain parts, thus enabling the user to assemble the parts of the device so that when a coin is inserted therein it will be automatically locked, preventing its removal until the seal is broken and the device taken apart, or to permit a coin or coins to be easily removed if desired.

The invention will first be hereinafter more particularly described, with reference to the accompanying drawings, which form a part of this specification, and then pointed out in the claims at the end of the description.

Figure 1 of the drawings represents a side elevation of a device embodying my in- 55

vention, showing in full lines a coin in position to be inserted and indicating in dotted lines the automatic locking mechanism with means for pushing a coin past the locking point; Fig. 2 is a vertical sectional elevation taken on the line 2-2 of Fig. 9, looking in the direction of the arrow, and showing in dotted and full lines a coin before and after its insertion in the entrance opening; Fig. 3 is a vertical sectional view similar to Fig. 2, showing the device with the parts in the position they occupy after it is filled with coins to its full capacity, the coin pushing device being shown obstructing the path of a coin that has traveled entirely around the coin raceway back to the entrance opening; Fig. 4 is a vertical sectional elevation taken on the line 4-4 of Fig. 9, looking in the direction of the arrow and showing the intermediate partition or diaphragm in full lines; Fig. 5 is a perspective view of the diaphragm detached; Fig. 6 is a perspective view of one member of the pawl-and-ratchet device for automatically locking the coins as they are inserted in the retainer so as to prevent backward movement; Fig. 7 is a fragmentary detail sectional view showing the pawl-and-ratchet devices in position for locking the coin within the retainer; Fig. 8 is a fragmentary detail sectional view showing the pawl-and-ratchet devices in reversed position to prevent locking the coin within the retainer; Fig. 9 is a vertical central transverse section of the receptacle shown in Fig. 1; Fig. 10 is a fragmentary detail sectional view, on a slightly enlarged scale, illustrating the mode of securing the diaphragm and the pawl-and-ratchet devices together so as to adapt them to be handled as a unit; Fig. 11 is a detail perspective view of a broken-away portion of the diaphragm, illustrating a modification of the spring catches formed thereon; Fig. 12 is an edge view of the receptacle shown in Fig. 1, looking at the entrance opening therein, and indicating in dotted lines the coin pushing devices on opposite sides of the diaphragm; Fig. 13 is a fragmentary detail sectional view of the central portion of the receptacle, illustrating a modification of the construction shown in Fig. 9; and Fig. 14 is a perspective view, on an enlarged scale, of a broken-away portion of one of the side plates of the casing or receptacle, showing a slot or mortise in its peripheral flange to receive a tenon on the diaphragm.

Referring to the drawings, in which the same reference letters are used to denote corresponding parts in different views, the letters A and A¹ denote the side plates of a casing or receptacle of circular form adapted to receive ten dimes, five of which may be placed on each side of a central partition or diaphragm B, by which the interior of the casing is divided into two compartments or annular raceways around which the coins may travel until the first coin inserted returns to the entrance opening a, provided for inserting the coins in succession. Said side plates may be formed or provided with peripheral flanges fitting one within the other, as shown more clearly in Fig. 9 of the drawings; said flanges having portions thereof cut away to form the entrance opening a and also having one or more registering slots a¹ either diametrically opposite said opening or at other points to receive tenons b and b¹ on said diaphragm. The tenon b is of sufficient length to span the opening a so as to provide a coin entrance opening at each side of the diaphragm of a width about equal to the width of the coin to be inserted therein, while the tenon b¹ engages the registering slots a¹, thus centering and holding the diaphragm in proper position between the two side plates so as to equally divide the space therebetween and prevent the diaphragm from tilting. If desired additional registering slots and tenons may be provided at other points around the periphery of the casing. The diaphragm B is centrally apertured and on each side thereof is placed a ratchet-wheel C, which is preferably star-shaped, or of the Geneva movement type, having a series of radial projections c and intermediate concavities c¹, which conform to the curvature of the coin to be placed therein. On one side of the ratchet-wheel or rotating element C, coincident with the projections c between which the coin is held and carried around the raceway, recesses or ribs c² are provided for engagement with spring catches or pawls b² on the diaphragm B, to prevent the ratchet-wheel from turning in a backward direction while permitting it to rotate freely in a forward direction. In the form shown the spring catches b² are integral with the diaphragm and may be constructed by slitting and bending parts thereof so as to form a tongue on each side adapted to successively engage the ribs or notches in the ratchet-wheel to prevent backward movement while capable of yielding on the reverse movement to permit the ratchet-wheel to rotate freely in the opposite direction. These spring catches may be so positioned that one will engage a recess on one ratchet-wheel while another on the opposite side of the diaphragm will engage another recess on the other ratchet-wheel substan-

tially in the same plane, as shown in Figs. 5 and 7, or nearly diametrically opposite each other, as shown in Fig. 11. The ratchet-wheels are adapted to revolve about a central axis while the diaphragm B is held stationary, and for convenience in assembling the diaphragm and ratchet-wheels are preferably secured together in such manner as to adapt them to be handled as a unit. To this end, the ratchet-wheels are centrally apertured coincident with the aperture in the diaphragm to receive an eyelet D, the ends of which may be swaged or bent against beveled edges of the metal surrounding the apertures in the ratchet-wheels, as shown in Fig. 10, thereby securing the several parts together with provision for rotation of the ratchet-wheels about said eyelet as an axis while the diaphragm is fixed and immovable. The opening through the eyelet D is preferably large enough to receive inturned centrally disposed bosses or protuberances a² on the side plates A, A¹, which are apertured to receive the shank of a rivet E, preferably made of lead or other suitable material and compressed to form a head on the inserted end of the shank for securing the two side plates together and providing a seal which must be broken to permit the receptacle to be taken apart. A washer or washers e may be placed on the rivet E at one or both sides of the side plates, as desired. The side plates and ratchet-wheels may be constructed of relatively thin sheets or plates of aluminum, thus combining lightness with strength, while the diaphragm or partition B is made of phosphor bronze or other suitable material which may be slotted and bent to provide resilient catches for engagement with the notches or ribs on the ratchet-wheels.

It may be desirable in some cases to secure the assembled parts together without using an eyelet or other means for securing the diaphragm and ratchet-wheels together so as to adapt them to be handled as a unit, and to this end, instead of utilizing the eyelet, the hub-like protuberances on the side plates may be fitted within the bore or opening through the center of the diaphragm and ratchet-wheels and secured together by means of a rivet E¹ of lead or other suitable material to provide a destructible seal, as already described with reference to Fig. 9; such modification being illustrated in Fig. 13 of the drawings. Each of the side plates A and A¹ are preferably provided with a series of openings therein as shown of less size than the coin which the receptacle is designed to receive, in order that the coins may be seen through such openings, enabling the user at a glance to determine the number of coins the device may contain, and by inspection through said openings to

observe the character of the coins inserted therein. But such openings are not essential and may be dispensed with if desired. For the purpose of moving the coins along the raceway as they are inserted through the entrance opening *a*, and thereby actuating the ratchet device to lock and retain the coin within the receptacle after it has passed beyond a given point, a pushing device *F* is 5 slidably secured in each raceway and positioned normally at the rear end of the entrance slot or opening *a* to adapt it to be slid back and forth across the path of the coin as it is inserted, so that when the coin 10 has reached the full line position shown in Fig. 2 of the drawings, in which it is shown resting on the concave seat provided therefor on one of the ratchet-wheels, it may be forced into the raceway by a forward movement 15 of the pushing device, thereby causing the ratchet-wheel upon which the coin is resting to turn until the notch thereon next succeeding the notch engaged by the spring catch at the time the coin was inserted is 20 engaged by the catch, whereupon the pushing device may be slid back past the entrance opening to permit the insertion of another coin, and this operation is repeated until the number of coins inserted has 25 reached the desired limit, at which time the first coin introduced will have traveled entirely around the raceway back to the entrance opening, but cannot escape because the tail piece *f* of the pushing device, which 30 has advanced to push forward the last inserted coin, will lie in the path of the coin which has traveled around the raceway to the position shown in Fig. 3. In this position no further movement of either the 35 coins or the pushing device is permitted, and to remove the coins it is necessary to break the seal or destructible rivet and take the device apart, after which the several parts may be restored to their normal positions and secured together in properly assembled relation by inserting another rivet and sealing the device, whereupon it may be again filled and returned to the bank or other depository to be again opened as before. 40

In order that the pushing device may not advance or recede beyond the required distance for the performance of its function, a stud or set screw *f*¹ thereon may protrude 45 through an arc-shaped slot *G* in the side plate and the length of this slot will determine the distance the pushing device may be moved either forward or back, for the purpose of actuating the ratchet-wheel and advancing the coins along the raceway as they are inserted one by one through the entrance opening.

While the device shown is especially designed for saving dimes, it may be constructed to hold coins of any other denomi-

nation, without any variation in construction other than a difference in size, according to the size of the coin with which it is intended to be used. It may also be made with more or less than two compartments 70 or raceways, so as to receive and retain a greater or less number of coins than ten, which number the illustrated device is designed to hold, and if desired, the raceway on one side may be adapted to receive and 75 retain coins of a different denomination from those on the opposite side, for example, a dime on one side and a nickle on the other, the only difference in construction necessary in such cases being the provision of an entrance opening of greater or less length and width and a raceway of corresponding width and depth, according to the size and width of the coin to be inserted, and a ratchet-wheel of such size that 80 the concave portions *c*¹ thereof will properly seat the coins as they are inserted.

In practical use the several parts of the device are ordinarily assembled in the position shown in Figs. 1 and 9, with the spring 90 catches on the diaphragm facing the recesses or ribs which they engage on the ratchet-wheels, as indicated in Fig. 7, but by simply reversing the position of the ratchet-wheels or turning them around so that the sides 95 thereof with the recesses therein will face the inner walls of the side plates instead of facing the diaphragm, as shown in Fig. 8, the device may be assembled or converted into a non-locking receptacle, in which the 100 coins may be inserted and removed at will by merely applying pressure of the finger through one of the eight openings in the side of the casing for the purpose of moving the coin in a backward direction and out 105 through the entrance opening.

It will be observed that the receiver or coin trap constructed as described utilizes space to the best possible advantage, the complete structure containing ten dimes being only a little larger than a standard silver dollar, and being very light it may be carried around in the pocket of the user without inconvenience.

While the side plates are preferably constructed of aluminum and the diaphragm of phosphor bronze, any suitable material may be used, such as sheet metal or steel or celluloid, and various other changes may be made in the details of construction and arrangement of parts without departing from the spirit and scope of my invention, hence I do not desire to be limited to the specific construction shown by way of illustration. For instance, the spring catches and stops 115 or recesses on the partition and ratchet wheels may be transposed by providing spring catches on the ratchet wheels engaging stops or recesses on the partition instead of spring catches on the partition engaging 120

125

130

stops or recesses on the ratchet wheels, and instead of a destructible seal or rivet for detachably securing the assembled parts together any suitable equivalent device may be employed for this purpose.

To prevent a coin from being moved around the raceway by pressure of the finger through the sight openings after it has advanced far enough, without first inserting another coin, a depressible stop b^3 may be arranged on the partition in the path of the radial arms of the ratchet wheel C, adapted to yield under pressure of the inserted coin and permit rotation of the ratchet wheel and to rise and prevent the next arm from passing until the stop is again depressed by inserting another coin.

Having thus described my invention, what I claim as new and desire to secure by Letters Patent of the United States is:

1. A coin container adapted to hold only a predetermined number of coins of a given denomination, comprising a narrow inclosing casing having a single narrow opening in its margin through which the coins are inserted edgewise, and a narrow coin raceway leading from said opening and back thereto; said race-way being of a width slightly in excess of the thickness of the coin and the outer wall thereof having spaced openings therein through which the coins are exposed to view, and means for pushing the coin along said race-way step by step until the coin first inserted returns to said opening; said means acting upon previously inserted coins through the coin last inserted.

2. A coin trap comprising a narrow casing having a filling opening and a coin raceway leading therefrom and back thereto of a width about equal to the thickness of the coin to be inserted flatwise through said opening, means in said raceway adapted to prevent backward movement of the coin while permitting forward movement thereof, and means adapted to be slid back and forth for pushing a coin past the opening and receding to permit the insertion of another coin; said pushing device being adapted to prevent the egress of a coin through said opening when it has traveled the length of the raceway.

3. A coin trap comprising a narrow casing having a filling opening and a plurality of coin raceways leading therefrom and back thereto of a width about equal to the thickness of the coin to be inserted flatwise through said opening, means in said raceways adapted to prevent backward movement of the coin while permitting forward movement thereof, and means in each raceway adapted to be slid back and forth for pushing a coin past the opening and receding to permit the insertion of another coin; said pushing device being adapted to pre-

vent the egress of a coin through said opening when it has traveled the length of the raceway.

4. A coin trap comprising a narrow circular casing having a filling opening in its periphery and a coin raceway leading from said opening around the casing and back thereto, said raceway being of a width about equal to the thickness of the coin, means within the raceway to prevent backward movement of the coin when moved to a given point past said opening, and means for pushing a coin past the opening adapted to recede and clear the path for the next succeeding coin after each forward movement; said means adapted to obstruct the path of an outgoing coin and prevent its egress through said opening.

5. A coin trap comprising a narrow casing of circular form having a filling opening in its periphery and coin raceways extending around its axis from said opening and back thereto, and a pushing device in each raceway adapted to be slid back and forth for pushing coins successively past said opening and receding after each forward movement to permit the insertion of another coin; said device being adapted to obstruct the path of an outgoing coin and prevent its egress through said opening.

6. A coin trap comprising a receptacle of circular form having an opening in its periphery and a partition separating it into two compartments each of a width about equal to the thickness of a coin adapted to be inserted flatwise through said opening, and means in each compartment for pushing the coins successively past said opening, said means being adapted to be slid back and forth so as to clear the way for the insertion of a coin after each forward movement and to obstruct the path of an outgoing coin and prevent its egress through said opening.

7. A coin trap comprising a casing of circular form composed of side plates having overlapping marginal flanges and an intermediate plate or partition between which and the outer wall of the casing at each side is provided a coin raceway of a width about equal to the thickness of a coin leading around the casing, a coin entrance opening in the periphery of the casing at the starting point of the raceway, and means adapted to be slid back and forth beside said opening to push forward a coin and return to permit the insertion of another coin, said pushing means being adapted to prevent egress of a coin through said opening after passing around the raceway, and means to prevent backward movement of a coin when moved past said opening.

8. A coin trap comprising a casing of circular form having a coin entrance opening in its periphery and composed of side plates

having overlapping marginal flanges and an intermediate plate or partition separating the casing so as to provide a raceway at each side of the partition leading around the casing from said opening and back thereto, means in said raceways to prevent backward movement of a coin, and pushing devices slidably fitted in said raceways adapted to push a coin past the opening and then move back sufficiently to permit the insertion of another coin; said pushing devices having tail pieces which obstruct the raceway and prevent the egress of a coin through said opening after it has traveled the length of the raceway.

9. A coin trap comprising a casing of circular form having a peripheral coin entrance opening and composed of side plates having overlapping marginal flanges and an intermediate plate or partition separating the casing so as to provide a raceway at each side of the partition leading around the casing from said opening and back thereto, pushing devices slidably fitted in said raceway adapted for pushing a coin along the raceway past said opening and to be then moved back sufficiently to permit the insertion of another coin, said pushing devices carrying tail pieces which obstruct the raceway to prevent egress of a coin through said opening after it has passed around the raceway, means in said raceways to prevent backward movement of a coin, and means whereby said side plates and partition are secured together and sealed so that the coin may not be removed until such seal is broken.

10. A coin trap composed of separable parts which are secured together by a destructible sealing device so that the coin may not be removed until such seal is broken, said trap being circular in form and having a peripheral filling opening and a coin raceway therein of a width about equal to the thickness of the coin to be inserted flatwise through said opening, means in said raceway to prevent backward movement of the coin while permitting forward movement thereof, and a pushing device adapted to be slid back and forth so as to push a coin past the opening and then recede to permit the insertion of another coin; said pushing device being adapted to prevent the egress of a coin through said opening when moving forwardly toward said opening.

11. A coin trap comprising a narrow circular receptacle having a peripheral coin entrance opening and composed of separable sides and a central partition with a coin raceway between said partition and each side, means for pushing a coin along the raceway past said opening adapted to be drawn back to permit the insertion of another coin, and means to prevent backward movement of a coin after it has been inserted and moved past said opening while permitting forward

movement, said pushing means being adapted to obstruct the raceway and prevent the egress of a coin through said opening when moving forwardly toward said opening, together with means whereby the several parts of the receptacle are held together and sealed so that the coin may not be removed until such seal is broken.

12. A coin trap comprising a casing of circular form having a partition therein providing a compartment on each side of said partition, an entrance opening for coin leading into each compartment, a coin pushing device adapted to be slid forward and back beside said opening for pushing a coin so as to clear the way for the insertion of another coin, and means associated therewith adapted to prevent backward movement of a coin when advanced by said pushing device, said means being reversible and adapted in a reverse position to permit backward movement of the coin out through said opening.

13. A coin trap comprising a casing of circular form having a partition therein providing a circular raceway at each side of said partition, a coin entrance opening leading into each raceway, a coin pushing device adapted to be slid forward and back beside said opening for pushing a coin so as to clear the way for the insertion of another coin; said pushing device having a tail piece which in the forward position thereof obstructs the opening so as to prevent the removal of a coin which has traveled the length of the raceway, and means associated therewith adapted to prevent backward movement of a coin when advanced by said pushing device, said means being reversible and adapted in the reversed position to permit backward movement of the coin out through the entrance opening.

14. A coin container adapted to hold only a predetermined number of coins of a given denomination, comprising a narrow inclosing casing having a single narrow opening in its margin through which the coins are inserted edgewise, and a narrow coin raceway leading from said opening and back thereto; said race-way being of a width slightly in excess of the thickness of the coin and the outer wall thereof having spaced openings therein through which the coins are exposed to view, means for pushing the coin along said race-way step by step until the coin first inserted returns to said opening; said means acting upon previously inserted coins through the coin last inserted, and means to prevent egress of the coin first inserted through said opening on its return thereto, together with means for sealing the container to prevent the removal of the coins until the seal is broken.

15. A cointrap comprising a narrow circular casing having a single opening in its periphery through which the coin may be in-

serted and removed, a raceway leading around the casing from and back to said opening, and means to prevent backward movement of a coin after its insertion past a given point in said raceway, together with means for pushing the coins along the raceway as they are inserted one at a time, the latter means being adapted to prevent the escape of a coin after traveling around the raceway back to said opening.

16. A cointrap comprising a narrow circular casing having a single opening in its periphery through which the coin may be inserted and removed, a raceway leading around the casing from and back to said opening, means to prevent backward movement of a coin after its insertion past a given point in said raceway, and means for pushing the coins along the raceway as they are inserted one at a time, the latter means being adapted to prevent the escape of a coin after traveling around the raceway back to said opening, together with means for securing the parts of the casing together with 25 a seal that will prevent the removal of the coins until the seal is broken to permit the device to be taken apart.

17. A coin receptacle composed of circular side plates having inturned overlapping flanges, a partition dividing the space between said plates into two compartments forming raceways around which a coin may travel flatwise, said raceways being of a width slightly greater than the thickness of 30 the coin to be inserted therein, a coin entrance opening in said flanges, means in said raceways to prevent backward movement of a coin after passing beyond a given point in the raceway, and pawl-and-ratchet devices 35 consisting of substantially star-shaped wheels having concave peripheral portions for seating and carrying the coins around the raceways, and pawls engaging ribs or notches in said wheels to prevent rotation 40 thereof in a backward direction.

18. A coin receptacle composed of circular side plates having inturned overlapping flanges, a partition dividing the space between said plates into two compartments 45 forming raceways around which a coin may travel flatwise, said raceways being of a width slightly greater than the thickness of the coin to be inserted therein, a coin entrance opening in said flanges, means in said raceways to prevent backward movement of a coin after passing beyond a given point in the raceway, pawl-and-ratchet devices 50 consisting of substantially star-shaped wheels having concave peripheral portions for seating and carrying the coins around the raceways and pawls engaging ribs or notches in said wheels to prevent rotation thereof in a backward direction, together with sliding dogs adapted to push the coins along the 55 raceways as they are inserted and to prevent

the escape of a coin through the entrance opening after it has traveled around the raceway.

19. A coin container adapted to hold only a predetermined number of coins of a given denomination, comprising a narrow inclosing casing having a single opening in its margin through which the coins are inserted edgewise, and a narrow coin race-way leading from said opening and back thereto; 70 said race-way being of a width slightly in excess of the thickness of the coin and the outer wall thereof having spaced openings therein through which the coins are exposed to view, means for pushing the coin along 75 said race-way step by step until the coin first inserted returns to said opening; said means acting upon previously inserted coins through the coin last inserted, and means to prevent backward movement of a coin when 80 forced past said opening, together with means to prevent egress of the coin through 85 said opening on its return thereto.

20. A coin trap comprising a narrow casing having a coin entrance opening in its 90 margin and a coin raceway leading therefrom around the casing and back thereto of a width slightly in excess of the thickness of the coin, means to prevent backward movement of a coin when moved past a given 95 point in said raceway, means whereby further movement of a coin beyond said given point is prevented independently of another coin, the latter means being adapted to be actuated by another coin inserted in said 100 opening for releasing the coin first inserted and permitting continued forward movement thereof, and means for sealing the trap so that the coins cannot be removed until said seal is broken.

21. A coin container adapted to hold only a predetermined number of coins of a given denomination, comprising a narrow inclosing casing having a single opening in its margin through which the coins are inserted 105 edgewise; the interior of the casing being divided into two compartments each forming a narrow coin race-way leading from said opening and back thereto; said race-way being of a width slightly in excess of 110 the thickness of the coin and the outer wall thereof having spaced openings therein through which the coins are exposed to view, and means in each of said race-ways for pushing the several coins along the race-way until the coin first inserted returns thereto; said means acting on previously inserted coins through the coin last inserted.

22. A coin trap consisting of a narrow casing having a single entrance opening 115 adapted to permit ingress and egress of a coin, a raceway leading from said opening around the casing and back thereto of a width slightly in excess of the thickness of a coin adapted to be inserted therein, and 120 125

120

means in said raceway adapted to prevent backward movement of the coin, said means being reversible to permit backward movement when desired.

5 23. A coin container adapted to hold only a predetermined number of coins of a given denomination, comprising a narrow inclosing casing having a single opening in its margin through which the coins are inserted
10 edgewise, a partition dividing the interior of the casing into two compartments so as to provide a narrow coin race-way on each side thereof leading from said opening and back thereto; each of said race-ways being
15 of a width slightly in excess of the thickness

of the coin and the outer wall thereof having spaced openings therein through which the coins are exposed to view, means in each of said race-ways for pushing the several coins along the same until the coin first inserted returns to said opening, and destructible means for sealing the container to prevent the removal of the coins until the seal is broken.

In testimony whereof I affix my signature 25
in the presence of two witnesses.
